UNITED STATES PATENT OFFICE.

JESSE ALEXANDER, OF BROOKLYN, NEW YORK.

DESIGN FOR A TYPE-WRITER-PLATEN FRAME.

No. 38,819.

Specification for Design.

Patented Sept. 17, 1907.

Application filed August 3, 1905. Serial No. 272,614. Term of patent 14 years.

To all whom it may concern:

Be it known that I, JESSE ALEXANDER, a citizen of the United States, residing at Brooklyn, Kings county, State of New York, have invented a new, original, and ornamental Design for Type-Writer-Platen Frames, of which the following is a specification.

Figure 1 is a front view of a typewriter platen frame embodying my design. Fig. 2

is a rear view of the same. Fig. 3 is a side view of the same.

What I claim is:

The ornamental design for a typewriter platen frame as shown.

JESSE ALEXANDER.
